UNITED STATES PATENT OFFICE.

MARCEL B. BESSON, OF NEW YORK, N. Y.

COMB.

1,330,675.

Specification of Letters Patent. Patented Feb. 10, 1920.

Application filed October 10, 1919. Serial No. 329,656.

To all whom it may concern:

Be it known that I, MARCEL B. BESSON, a citizen of the United States, residing at New York, in the county of New York and 5 State of New York, have invented new and useful Improvements in Combs, of which the following is a specification.

This invention relates to improvements in combs and more particularly to a sanitary 10 comb so constructed as to greatly facilitate the cleaning of the same.

In the types of combs now in general use, it is very difficult to remove dirt and grease from between the teeth, the same being usually accomplished by running a wire or cord between the teeth, which not only consumes a great deal of time but is a very tedious 15 operation.

It is therefore the principal object of this 20 invention to provide a comb including a tooth supporting member in which are mounted a plurality of revoluble teeth whereby a brush may be used in cleaning the same by rubbing the bristles across the comb to revolve the teeth for removing foreign matter 25 from all sides of the same with little or no effort.

Another object of the invention is to provide a comb comprising a tooth supporting 30 member having revoluble teeth removably mounted therein, whereby a broken or mutilated tooth may be readily replaced by a new one by removing the cover.

A further object of the invention is to 35 provide a simple and inexpensive form of comb in which provision is made for varying the space between the teeth without weakening the structure or detracting from the rigidity of the teeth.

40 With these and other objects in view which will be more apparent as the nature, purpose and operation is more clearly understood, reference is made to the following description, claims and accompanying drawings, in which:

Figure 1 is a side elevation of a comb constructed in accordance with the invention, parts being broken away to disclose the underlying structure.

50 Fig. 2 is a fragmentary horizontal sectional view on the line 2—2 of Fig. 1.

Fig. 3 is a transverse sectional view on line 3—3 of Fig. 1.

55 Fig. 4 is a similar view on the line 4—4 of Fig. 1.

Fig. 5 is a view of a modified form of the invention.

Referring to the drawings by characters of reference, 10 designates a hollow tooth supporting member, which is provided with bottom, side and end walls 11, 12, and 13 respectively, the said bottom wall is preferably provided with a plurality of spaced apertures 14, through which are projected the circular teeth 15, the inner ends of the 60 same being enlarged to form circular heads 16. A cover member 17 is adapted to close the open side of the supporting member 10, after the teeth have been positioned therein. The length of the heads 16 are equal to the 65 distance between the bottom wall 11 and cover member 17, and the diameter of said heads are approximately equal to the space between the walls 12. By the arrangement 70 just described, it will be seen that when the 75 bristles of the brush are frictionally passed over the teeth, the same will be revolved in the supporting member for the easy cleaning of all of the sides of the same. It will be further noted that the heads 16 are confined within the supporting member and 80 coact with one another to maintain the proper rigidity of the teeth relative of the supporting member.

The majority of combs now in use, 85 comprise coarse and fine teeth and the teeth 15, just described and appearing at the left half of Fig. 1, represent the coarse section of the comb. In order to provide fine teeth which can be associated with the same tooth 90 supporting member, without materially weakening the structure or detracting from the rigidity of the teeth, an arrangement such as shown at the right half of Fig. 1 is utilized and comprises teeth 18, having 95 circular heads 19, the latter being approximately one half of the height of the heads 16. The lower half of the side walls between which the heads 19 are mounted are thickened to provide a snug fit for the reduced 100 diameter of said heads. The teeth 20 are substantially longer than the teeth 18 and are provided with circular heads 21 and are substantially of the same diameter of the heads 16 said heads being adapted to occupy 105 the place between the upper ends of the heads 19 and the cover member 17. The teeth 18 and 20 are alternately arranged within the apertures 22 which apertures are placed closer to each other than the aper- 110

tures 14 and it will be seen that the heads 19 are separated from each other by that portion of the tooth 20 which extends from the head 21 to the inner surface of the wall 5 11. In assembling the comb the teeth are dropped through the openings, the teeth 18 being first inserted and the teeth 20 positioned thereafter. The cover member 17 is then secured in place on the support by any 10 desired fastening means.

In the modified form illustrated in Fig. 5 of the drawings, the heads 16 are provided with semi-spherical centering lugs 23 which are adapted to be received by the bearings 15 24 formed in the cover member 17. The engagement of the lugs with the bearings serve to aline the teeth in the openings and prevent lateral play of the teeth, thereby adding 20 to the rigidity of the same.

25 No limitation is made to the precise structure set forth and shown, said showing being merely illustrative of one means of reducing the invention to practice and it is understood that equivalent structures which would be covered by the claims may be resorted to when desired.

What is claimed as new is:—

1. A comb comprising a hollow apertured tooth supporting member, a plurality of rev- 30 oluble heads mounted therein and teeth formed on said heads and extending outwardly through said openings.

2. A comb comprising a hollow apertured tooth supporting member, a plurality of rev- 35 oluble circular heads mounted therein for co-acting engagement with each other and teeth formed on said heads and extending outwardly through said openings.

3. A comb comprising a tooth supporting member including bottom, side and end 40 walls, said bottom wall having a plurality of spaced alined apertures, a cover for said supporting member, circular heads adapted to be confined within the supporting mem- 45 ber for rotation, and teeth formed on said heads and extending outwardly through the apertures in said bottom wall.

4. A comb comprising a tooth supporting member, bottom, side and end walls, and a cover therefor, said bottom wall having a 50 plurality of spaced alined apertures, one half of which are relatively widely spaced with respect to the remainder, circular heads adapted to be confined for rotation within the supporting member, teeth formed on 55 said heads and extending outwardly through the widely spaced openings, a second set of alternately superposed heads confined for rotation in said supporting member, and teeth formed thereon and extending through 60 the remaining openings.

In testimony whereof I hereby affix my signature.

MARCEL B. BESSON.
